(57) **CLAIM**

The ornamental design for a coffee machine as shown and described.

DESCRIPTION

FIG. 1 is a front view of a coffee machine according to the new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a perspective view thereof; and,

FIG. 8 is an enlarged detail perspective view of the portion 8 identified in FIG. 7.

The dot-dash broken lines depict the boundaries of the detail enlargement and form no part of the claimed design.

1 Claim, 8 Drawing Sheets
